A. R. Appelman

UNITED STATES PATENT OFFICE.

ALEXANDER FRANK AND ERNST CHARLES KOPSTEIN, OF NEW YORK, N. Y.

COMBINATION-WEAPON.

1,323,973.

Specification of Letters Patent.

Patented Dec. 2, 1919.

Application filed September 22, 1915, Serial No. 52,126. Renewed March 15, 1918. Serial No. 222,739.

To all whom it may concern:

Be it known that we, ALEXANDER FRANK, a subject of the Czar of Russia, and ERNST CHARLES KOPSTEIN, a citizen of the United

5 States, both residents of New York city, New York, have invented a new and useful Improvement in Combination-Weapons, of which the following is a specification.

This invention relates to improvements 10 in combination weapons, the object being to provide an automatic gun shaped to form a handle or grip and a hand-guard for a sword, which has integral extensions adapted to form the side walls of the magazine chamber of the gun and be secured thereto.

A further object being to provide a military weapon comprising the combination of an automatic gun and a sword for cavalrymen to enable them to have better control 20 of their horses when in action.

A still further object being to provide an improved combination weapon of new and novel construction and arrangement of parts 25 which will be hereinafter more specifically described and claimed.

In carrying out our invention, we may substitute a club for the sword to be used by policemen or other officers.

30 In the drawings forming part of this specification similar reference characters are employed to designate corresponding parts throughout the several views and in which:—

35 Figure 1 is a side view of a combination weapon constructed according to our invention;

Fig. 1^a is an enlarged sectional elevation showing an automatic gun mechanism;

40 Fig. 2 is a sectional plan taken at 2—2 of Fig. 1^a, parts being broken away to more clearly show the construction;

Fig. 3 is a vertical section on the line 3—3 of Fig. 1^a;

45 Fig. 4 is a perspective of a plunger block employed;

Fig. 5 is an elevation of a magazine case employed; and,

Fig. 6 shows a modified embodiment of 50 the invention.

Referring to the drawings, we provide a frame or casting 10 shaped to form a handle or grip 11, and a guard 12, to protect the hand, and within the handle 11 is provided 55 a magazine chamber 13, having partially open sides and open ends as shown, and the

handle portion is further provided with a chamber 14 adapted to house some of the operative mechanism, as will be hereinafter described.

60 The frame or casting 10 is provided with a barrel or bore 15, to receive the cartridges in the operation of the gun, and slidably mounted on this frame is a plunger block 16 provided with a semi-tubular front extension 17, which incloses the barrel and a similar rear extension 18, which forms the top of the chamber 14, as clearly shown in Fig. 1^a.

65 The plunger block 16 is further provided with oppositely arranged spring chambers 19—19 designed to receive the outer or front ends of compression springs 20, and the plunger block is also provided with a shell ejecting opening 21 and with a spring 22 pressed pivoted hook 22 adapted, in the operation of the gun, to engage the flange of the shell and withdraw it from the barrel to be later ejected through the opening 21, and a registering opening 23 formed in the 80 forked shank portion 24 of a sword member 25, as clearly shown in Fig. 3.

We also form in the plunger block a central bore 26, which receives an outwardly 85 spring pressed firing pin 27 adapted to be acted upon by a spring-operated hammer 28 controlled by a spring pressed trip dog 29, having a shoulder 30 to engage a corresponding shoulder 31, on the hammer to retain the latter in a cocked or inoperative 90 position.

The trip dog 29 is operated by a yoke 32, the arms of which straddle the magazine chamber and at the front these arms are connected and provided with a trigger button 95 33, arranged in a recess 34, in the frame 10, so that the user may manipulate the sword without operating the gun, but as a further guard against accident we form in one of the arms of the yoke 32, a recess 35, adapted to receive a locking lug provided on a slide plate 36, as shown in Figs. 1^a and 3.

We provide stop pins 42 to limit the forward travel of the plunger block 16, which are easily removed to take the gun apart.

105 The shank portion 24 of the sword 25, is shaped to form housings 37, to slidably receive the spring chambers 19—19, and said housings have integral rear walls 38 against which the rear ends of the springs 20 bear, 110 as clearly shown in Fig. 2 of the drawings, and below the housings 37 the shank por-

tion 24 is shaped to form cheek plates 39, which form the side walls of the magazine chamber and are secured in place by screws or other fastening devices.

5 In Fig. 5 of the drawings, we have shown a magazine case 40 provided with the usual cartridge feeding means which we will not describe as it forms no part of our invention.

10 In Fig. 6 we have shown another embodiment of our invention in which a policeman's club 41 is substituted for the sword.

The automatic action of the gun is the same as other guns of this class and needs 15 no description of operation.

Changes in and modifications of the construction and arrangement of parts, as herein shown and described, may be resorted to within certain limits, without departing 20 from the spirit of our invention, or the scope of the appended claims.

What we claim is:—

1. In a weapon of the class described, a gun provided with a plunger block provided 25 with opposite spring chambers, a sword having a forked shank shaped to slidably receive the spring chambers, means for feeding cartridges to the gun and for firing the same as shown and described.

30 2. In a combination weapon, an automatic gun provided with a plunger block having opposite spring chambers adapted to receive the forward ends of compression

springs, a sword having a shank provided with housings to receive said spring chambers, said housings having integral end walls against which the rear ends of the springs bear, means for feeding cartridges into the gun and means for firing the same as described. 35

3. The combination with a gun having a sliding plunger block provided with opposite spring chambers of a sword having a forked shank shaped to receive the said spring chambers and to house the springs 40 45 as shown and described.

4. In a combination weapon, a frame provided with a magazine chamber and a barrel, a reciprocating plunger block mounted on the barrel, said plunger block having 50 semi-tubular front and rear extensions and oppositely disposed spring chambers, and a sword having a shank shaped to receive the said spring chambers and to form the sides 55 of the magazine chamber as shown.

5. In a weapon of the class described, in combination, a gun having a plunger block provided with front and rear semi-tubular extensions and a sword having a forked shank adapted to straddle the gun and close 60 the sides of the magazine chamber.

In testimony whereof, we have signed our names to this specification, this 14th day of September, 1915.

ALEXANDER FRANK.
ERNST CHARLES KOPSTEIN.
